UNITED STATES PATENT OFFICE.

GRENVILLE MELLEN, OF CRANFORD, NEW JERSEY.

METHOD OF AND APPARATUS FOR CASTING HOLLOW BARS OR TUBES.

1,342,127.

Specification of Letters Patent.

Patented June 1, 1920.

Application filed May 14, 1919. Serial No. 297,120.

To all whom it may concern:

Be it known that I, GRENVILLE MELLEN, a citizen of the United States, residing at Cranford, in the county of Union and State of New Jersey, have invented certain new and useful Improvements in Methods of and Apparatus for Casting Hollow Bars or Tubes, of which the following is a specification.

10 My invention relates to a method and apparatus for casting hollow bars or tubes and has for its object to cast such hollow bars or tubes of lengths longer than can be obtained by the ordinary methods of casting in molds.

15 It has heretofore been difficult to make rod or tube castings of certain alloys, such as bronze used for making bushings, in lengths relatively long as compared with the diameter, because of the tendency of this material to crack in the mold or to form imperfect castings, also containing blow-holes and gas voids.

20 These difficulties I overcome by a method and apparatus which are based on the principles of operation disclosed in my prior Patents Nos. 1,139,885, 1,139,886, 1,139,887, 1,139,888 and 1,139,889, patented May 8, 1915, and in my allowed application Ser. No. 34,735, filed June 17, 1915.

25 The invention will be understood from the accompanying drawings in which—

Figure 1 is a transverse vertical section through the casting tubes;

30 Fig. 2 is a vertical section on a plane at right angles to that of Fig. 1;

Fig. 3 is a horizontal section on plane 3—3 of Fig. 2; and

35 Figs. 4, 5, 6 and 7 are cross-sectional views of various forms of tube-rod castings.

The machine shown is of the vertical type shown in my Patents Nos. 1,139,888 and 1,139,889, only such details of construction being shown in the present application as relate to this particular invention.

40 In this type of machine, the mold cavity is formed by and between two endless chains of mold blocks having suitable shaped mold cavities therein. As shown in Fig. 3 the 45 mold blocks B, B' each have central and side semi-cylindrical cavities, which when the blocks are brought into metal-sealing engagement form three connected vertical mold chambers, the central chamber being shown 50 of larger diameter than the side chambers although this is not an essential feature.

As shown in Fig. 1, the metal is delivered from the pouring pot 6 into the side chambers and flows into the central mold chamber which is provided with a centrally located 60 core, so that as the mold-chains move downward, there is formed a composite casting consisting of a central hollow or tube portion connected to and integral with two solid rod portions.

65 The flow of metal from the pouring pot into the side mold cavities is controlled by two valves 7, 7, mounted as shown in Fig. 2 on the ends of pivoted levers 80, pivoted on bars 21, carried by a post 22 mounted on 70 the frame of the machine. A spring or counterbalance 23 facilitates ease of operation. 24 is a suitable stop device. These valves may be operated manually or by the automatic means described in my Patent No. 75 1,139,888.

75 The pouring pot 6 is provided with two tubes 5 extending downwardly into the side mold chambers, and has an upwardly extending guide tube 20, through which the 80 cores are introduced into the central mold chamber.

85 The cores are made in the usual manner and may consist of a core-barrel 3, of iron pipe with perforations through the wall to permit the escape of gases to the interior of the pipe and their free escape out of the pipe. This core-barrel is surrounded by a covering 26 consisting preferably of a layer of steamed hay upon which is plastered core 90 clay and sand so that the core is sufficiently compressible to take care of the contraction of the metal as it cools.

95 The core-barrels 3 extend at each end of the core beyond the core covering 26. These extensions fit into core-bits 9 of steel or iron tubing having an interior diameter sufficient to permit the insertion of the core-barrel and an exterior diameter fitting the central bore or mold chamber, these core-bits serving to center the core in this central mold chamber.

100 Mounted above the pouring pot is a tubular core guide 8, held in position by stays 27 to the framework of the building or to the 105 frame of the machine and by a guide ring 28. Turnbuckles 11 and adjusting screws 29 enable the core guide 8 to be properly centered.

110 The operation of the machine is as follows: To commence the operation, a piece of sheet metal is installed between the mold

sections at the upper end of the machine, as they turn about the sprockets at the upper end of the machine, this piece of sheet metal extending at right angle to the length of the 5 mold chambers across the mold cavity forming an initial bottom for the first pouring. After this piece of sheet metal has progressed to the proper distance a core-bit is dropped into the center bore and is 10 supported by said piece of sheet metal. A core is then lowered into the center bore, and the end of the core-barrel inserted into the core-bit. A second core-bit is located on the upper end of the core-barrel and the 15 lower end of a second core-barrel is inserted into the upper end of this second bit, this second core coming down through the core-guide 8. A succession of cores, centrally guided, is thus passed down through the 20 central mold chamber.

At the proper time the valves 7, 7 are 25 opened and molten metal flows down into the two side mold chambers and thence into the central mold chamber around the core to form the central tube. As the mold blocks move downward, the triple tube-rod casting 39 having the shape shown at the bottom of Fig. 1 and in Fig. 3 is produced and of any desired length. There is of 30 course considerable latitude in respect to the cross-sectional configuration of the mold and the tube-rod casting. Figs. 4, 5, 6 and 7 indicate various forms serving as examples. Figs. 4 and 5 show forms similar to 35 that disclosed in Figs. 1 and 3, but differing as to the thickness of the webs connecting the lateral rods with the central tube. Figs. 6 and 7 are modifications showing tubes interconnected by a central solid rod portion.

When a casting has been formed of the desired length, the supply of metal is cut off and a new casting is made; or, the feed of metal is stopped for a moment to allow 45 a coating of oxid or scum to form on the top of finished casting, so that there will be no fusion to the end of the next casting as it comes along.

The central tube is severed from the side 50 rods by passing through suitable dies which cut the connecting webs, or the webs may be severed in any other suitable manner. By this method of casting, a sounder, denser product, substantially free from blow holes and 55 or gas voids is obtained. The method is moreover applicable to the casting of metals or alloys which it is difficult to cast in lengths which are long as compared with the diameter by any other method known to me. Thus in the manufacture of bronze rods or tubes the length of the casting is limited only by the height of the machine to which the machine is elevated.

I believe that I am the first to make a 60 sound bronze rod or tube casting of greater

length than thirty-six times the diameter. The advantage of having such longer lengths will be apparent to those familiar with the art.

By the method of pouring into the side 70 mold chambers, central tubes of relatively small diameter may be made; when larger tubes are desired it is feasible to pour the molten metal directly into the tube-forming chamber, since in such case there will be 75 space enough to admit a feed tube into such chamber.

My method may further be varied, where the sectional areas are large enough, by extending cores into the side bores and feed- 80 ing the metal through the center bore; but, feeding the metal from both sides around the central bore has the advantage that the molten metal more rapidly envelops the core to form a tube.

I claim:

1. The method of casting tubes which consists in locating a core within a mold chamber formed by a series of traveling coöperating mold-sections, and delivering molten 90 metal into said chamber about said core during the movement of the mold sections and the core located therein.

2. The method of casting rods or tubes which consists in delivering molten metal 95 into a moving mold having several mold forming bores therein, at least one of which has located therein a central core, the metal being delivered into a rod-forming bore and flowing therefrom into the tube-forming 100 bore.

3. The method as claimed in claim 2 in which the molten metal is delivered into two bores and flows therefrom around the core in a central bore.

4. A casting machine comprising a series of traveling sections fitting together to form a continuous mold chamber, a core arranged to travel with said traveling mold sections, and means for holding the core in position 110 during its travel through said mold chamber.

5. A casting machine as claimed in claim 4 in which the means for holding the core in position comprise tubes fitting over the 115 ends of the core and fitting within said mold chamber.

6. A casting machine comprising a series of traveling coöperative mold blocks fitting together to form a series of connected mold-forming chambers or bores, means for centrally locating a core in at least one of said chambers, and means for delivering molten metal into said chambers.

7. A casting machine as claimed in claim 125 6 in which the core is located in a central mold chamber, and a mold chamber is provided on each side of said central mold chamber.

8. A casting machine as claimed in claim 130

- 7 having a pouring pot, and means for delivering molten metal therefrom into each of said side molding chambers.
9. A casting machine as claimed in claim
5 7 in which the central mold chamber is of larger diameter than the side chambers.
10. A casting machine as claimed in claim
6 having a tubular core guide arranged above one of said mold chambers.
- 10 11. A casting machine as claimed in claim

6 having an adjustable tubular core guide arranged above one of said mold chambers.

12. A casting machine as claimed in claim 6 in which the cores have barrels extending beyond the ends of the core covering, said 15 ends extending into tubular core-bits fitting within the mold chamber.

In testimony whereof I affix my signature.

GRENVILLE MELLEN.
